UNITED STATES PATENT OFFICE.

DANIEL WENTLAND, OF PETTIBONE, NORTH DAKOTA.

GANG-PLOW.

1,109,806.

Specification of Letters Patent. Patented Sept. 8, 1914.

Application filed September 17, 1913. Serial No. 790,185.

To all whom it may concern:

Be it known that I, DANIEL WENTLAND, a citizen of the United States, residing at Pettibone, in the county of Stutsman and State of North Dakota, have invented a new and useful Gang-Plow; and I do hereby declare the following to be a full, clear, and exact description of the invention, such as will enable others skilled in the art to which it appertains to make and use the same.

This invention relates to a new and useful improved gang plow, more especially adapted for plowing sides of a steep hill or low mountain sides.

One of the objects of the invention is to provide a gang plow of this nature comprising desirable and practical features of construction.

One of the features of the invention is the provision of means whereby two plows may be simultaneously lowered so that the points thereof will enter the soil.

In practical fields the details of construction may necessitate alterations, to which the patentee is entitled, provided the alterations fall within the scope of what is claimed.

The invention comprises further feature and combination of parts as hereinafter set forth, shown in the drawings and claimed.

In the drawings:—Figure 1 is a view showing the plows raised. Fig. 2 is a side elevation showing the plows lowered.

Referring more particularly to the drawings, 1 designates a member having at the rear a seat 2. Mounted in a bearing 3^a of the member 1 at its forward portion is the arch portion 3 of an axle 4. This axle is provided with lateral stubs or portions 5, on which supporting wheels 6 are journaled. 40 Mounted also on the members 1 are the beams 7 and 8 secured in place by the bolts 8^a. The rear ends of the beams are secured at 9 to the mold boards 10 of the plows 11. The forward ends of the beams are connected by a transverse pin 12, on which a clevis 13 is arranged, and to which clevis any suitable everer (not shown) may be connected, whereby the apparatus may be drawn by draft animals.

50 Rising upwardly and extending forwardly in the member 1 is a rack 14 secured in place at 14^a, and braced by the bar 20. Forming an integral part with the arch 3 is a lever 15 having a tooth 16, adapted for engagement with the rack to hold the lever in adjusted positions. However, when the wheels

and the arch portion of the axle are disposed as shown in Fig. 1, the lever 15 rests upon the headed lug 19, which prevents the lever from moving downwardly, and since the 60 weight of the operator is upon the member 1, and the arch portion on an angle as shown in Fig. 1, the lever 15 will press against the lug 19, so as to hold the wheels and the lever in adjusted positions. The weight of the 65 operator on the seat constitutes means not only to co-act with the lug 19 to hold the sides of the axle inclined downwardly and forwardly, but to co-act with the rack and the tooth 16 on the lever to hold the sides 70 of the axle inclined rearwardly and downwardly, so that the plow is directed downwardly in the soil. When the wheels are adjusted as shown in Fig. 2, the tooth 16 engages one of the teeth of the rack 14, 75 which will hold the wheel and the lever in position.

Referring to Fig. 1, it will be seen that by moving the lever in the direction of the arrow 18, the wheels may be thrown rearwardly. In this manner the forward portion of the member 1 is lowered together with the beams 7 and 8, thereby causing the plow point to enter the soil.

The invention having been set forth what 85 is claimed as new and useful is:—

A sulky gang plow comprising a heavy member provided with a seat for an operator rising from the rear portion, plow beams including plows rigidly fixed to diametrically opposite sides of said member, the upper face of said member at its forward portion being provided with a bearing, an arched axle mounted in said bearing, the sides of the arch axle being diametrically 90 opposite and normally inclined downwardly and forwardly and provided with wheels, one side of the arch axle having a rearwardly extending lever, a lug projecting laterally of said member on which the lever 100 engages to hold the sides of the axle normally inclined downwardly and forwardly, a segmental rack rising from said member, said lever constituting means whereby the sides of the axle may be inclined downwardly and rearwardly, said lever having 105 means to engage the rack to assist in holding the sides of the axle inclined rearwardly and downwardly, the seat being so arranged relative to the member, the axle and the 110 said plow beams, that the weight of the operator on the seat constitutes means not only

to co-act with said lug to hold the sides of the axle inclined downwardly and forwardly, but to co-act with the rack and the means on the lever to hold the sides of the 5 axle inclined rearwardly and downwardly, so that the plow is directed downwardly in the soil.

In testimony whereof I have signed my name to this specification in the presence of two subscribing witnesses.

DANIEL WENTLAND.
